The ornamental design for a toilet paper roll holder, as shown and described.

DESCRIPTION

FIG. 1 is an environmental front elevational view of a toilet paper roll holder showing my new design;
 FIG. 2 is an environmental right side elevational view with the left side being a mirror image thereof;
 FIG. 3 is an environmental top plan elevational view thereof;
 FIG. 4 is an environmental bottom plan view thereof; and,
 FIG. 5 is a reduced scale, environmental perspective view thereof.

The undisclosed rear is plain and unornamented. The broken line showing of the toilet paper is for illustrative purposes only and forms no part of the claimed design. The broken line showing of the stand in FIG. 5 is for illustrative purposes only, merely showing one of many types of stands that can be used with the invention, and forms no part of the claimed design. The broken line showing of the toy bear in FIGS. 1-4 is for illustrative purposes only, merely showing the types of objects that can be used with the invention, and forms no part of the claimed design.
